 4 Claims. (Cl. 313—94)

This invention relates to photo-electron emissive discharge devices in which image intensification can be achieved by accelerating the photo-electrons and causing them to impinge on a target with a high velocity. The invention is applicable for example to image intensifiers, photo-multiplier devices or television or other image pick-up devices.

It has been found that in photo-electron emissive discharge devices in which image intensification is achieved by accelerating photo-electrons and causing them to impinge on a target with a high velocity, spurious noise signals are liable to be produced, which signals cannot be accounted for by the more usual causes of spurious signals.

The object of the present invention is to provide an improved photo-electron emissive discharge device in which image intensification can be achieved by accelerating the photo-electrons and causing them to impinge on a target with a high velocity, with a view to reducing the liability for spurious signals to be produced.

It has been found by the inventors that the spurious signals above referred to arise because positive ions can be produced at or near high voltage electrodes in discharge devices in which the photo emissive electrons are accelerated to a high velocity by the electric field in the device. Such ions may be liberated especially from the surface of the target on which the photo-electrons impinge and the ions so liberated may be accelerated by the electric field which acts on the electrons, but in the opposite direction to the electrons so that they arrive at the photo-electron emissive cathode with sufficient energy to release secondary electrons. These in turn travel to the target and give rise to the spurious signals. For example in an image intensifier positive ions released from the surface of the luminescent screen in which the intensified light image is produced may impinge on the photo-cathode with energies of 10 kilovolts or more and each ion may produce several secondary electrons.

Having regard to the cause of the spurious signals found by the inventors, there is provided, according to the present invention, a photo-electron emissive discharge device comprising a photo-electron emissive cathode for converting incident light into an electron stream, a target for said electron stream, said target being arranged to receive a high voltage so that electrons of said electron stream can impinge on the target with a high velocity and wherein to reduce the release of ions from the surface of the target on which the photo-electrons impinge is provided with a porous coating formed by evaporation of metal onto the surface of the target in a gaseous atmosphere, which coating tends to trap such ions.

It is believed that the porous coating is effective because the ions remain trapped for a sufficient time to enable their charge to be neutralised. The porous coating is a metal coating formed by evaporating a suitable metal in a gaseous atmosphere.

Any other electrode at which when the device is operating the electric field intensity is sufficient for release

of ions may also be provided with a porous coating. For example an accelerating electrode or more than one accelerating electrode disposed between the photo-cathode and the target may be provided with a porous coating.

5 A further spurious noise signal may be set up in a photo-electron emissive discharge device by reflected light feedback. For example if the photo-emissive cathode of the device is semi-transparent, as in the case of an antimony photo-cathode sensitised with caesium or with a plurality of alkali metals, some incident light, particularly at the long wave end of the visual spectrum may pass through said photo-cathode and subsequently be reflected back to said photo-cathode by other electrodes in the device or by glass or aluminised surfaces for example. In one embodiment of the invention the above 15 mentioned porous coating is of such a material as to provide an intense, black, non-reflecting surface so as to reduce said light reflection.

In order that the invention may be clearly understood and readily carried into effect it will now be more fully described with reference to the accompanying drawings of which:

FIGURE 1 shows one form of photo-electron emissive discharge devices according to an embodiment of the invention, and

25 FIGURE 2 is a detail of FIGURE 1 on an enlarged scale.

The invention will be described with reference to the drawing, by way of example, as applied to a single stage image intensifier which comprises a substantially cylindrical envelope 1 having on one end wall a photo-electron emissive cathode 2 which may by way of example be of antimony sensitised with caesium or a plurality of alkali metals. On the other end wall of the envelope 1 there is formed a luminescent screen 3. Between the photo-cathode 2 and luminescent screen 3 there is provided an annular accelerating electrode 4 and during operation of the device, the envelope 1 will be surrounded by a focusing coil and the electrode 4 and screen 3 will be maintained at high positive potentials with respect to the photo-cathode 2.

The luminescent screen 3 is shown in greater detail in FIGURE 2 and comprises a layer 5 of luminescent material which may be formed on the end wall of envelope 1 by gravity deposition or electrophoresis. The layer 5 is covered with a layer 6 of aluminum which is evaporated in a high vacuum, for example at a pressure of 2×10^{-5} millimetres of mercury, the layer 6 having a thickness between 250 Å. and 1,000 Å. The layer 6 is then covered by a porous coating 7 which may also be of aluminium evaporated in an atmosphere of an inert gas such as argon at a pressure between 0.2 and 2 millimetres of mercury. By way of example a coating 7 of suitable thickness may be formed by evaporating 10 milligrams of aluminium at a distance of $3\frac{1}{2}$ inches from the surface on which it is to be deposited, the area of the surface being about 20 sq. cms.

60 The porous coating 7 of aluminium provides a black non-reflecting surface, and a similar coating may, if desired be provided on the electrode 4. In the case of the luminescent screen of an image intensifier it is desirable that the porous coating 7 should not substantially reduce the energy of penetrating electrons and for this purpose a low density material such as aluminium for the porous coating is particularly desirable. In other cases where density is not so important as on the electrode 4, for example, other materials may be used to form the porous coating. Examples of such materials are gold and silver.

When the device which is illustrated in FIGURES 1 and 2 is in operation it is connected to an external circuit in such a way that the accelerating electrode 4 is maintained at a positive potential of 5 kilovolts with respect to the

photo-cathode 2 whilst the aluminium layer 6 on the luminescent screen 5 is maintained at a positive potential of 10 kilovolts, also with respect to the photo-cathode 2. The intensifier is moreover disposed inside a focussing solenoid which produces the magnetic field parallel to the axis of the intensifier.

In the particular image intensifier described and illustrated only one accelerating electrode is provided, but if desired two or more such electrodes may be provided, any or all of which can be provided with a porous coating. Moreover, the invention is also applicable to image intensifiers having a plurality of stages, each with a photo-cathode, in which case one or more of the luminescent screens may include a porous layer. The invention can also be applied to other photo-electron emissive devices such as image orthicons or other television or image pick-up tubes or photo-multiplier devices.

One type of television or image pick-up tube to which the invention is especially applicable is a tube of the type in which the target comprises a layer of insulating material which exhibits electron bombardment induced conductivity. In a tube of this type the photo-electrons from the photo-cathode impinge on the target with a very high velocity, in the order of 10 kilo electron volts. The image electrons are therefore particularly liable to liberate positive ions from the surface of the target on which they impinge. It will be understood that in a tube of this type the conductivity induced by the image electrons causes charges to be accumulated on different elemental areas of the target. These charges are discharged periodically by scanning the target with a low velocity electron beam, for example. If electron beam scanning is employed, the scanning section of the tube is generally of a similar construction to the scanning section of an image orthicon.

It will be understood that the invention is also applicable to image intensifiers which are constructed integrally with television pick-up tubes.

What we claim is:

1. A photo-electron emissive discharge device comprising a photo-electron emissive cathode for converting incident light into an electron stream, a target for said electron stream, said target being arranged to receive a

- high voltage so that electrons of said electron stream can impinge on the target with a high velocity and wherein to reduce the release of ions the surface of the target on which the photo-electrons impinge is provided with a porous coating formed by evaporation of metal onto the surface of the target in a gaseous atmosphere, which coating tends to trap such ions, said device constituting an image intensifier and in which said cathode converts an incident light image into an electron image which in operation of the device impinges on said target, and said target comprises a luminescent layer having a conducting metallic layer formed on the surface of the luminescent layer facing said cathode by evaporation in a high vacuum, said porous layer being provided on said conducting layer.
- 5 2. A device according to claim 1 in which said porous coating comprises aluminium.
3. A device according to claim 2 in which said porous layer is produced by evaporating aluminium in an inert 10 gas at a pressure between 0.2 and 2 millimetres of mercury.
- 20 4. A device according to claim 1 in which said porous layer is black.
